BY

H. J. Fisher ATTORNEY

INVENTOR
OTIS B. BENTON

UNITED STATES PATENT OFFICE.

OTIS B. BENTON, OF CLEVELAND, OHIO.

CLOSED-CONDUIT ELECTRIC RAILWAY.

SPECIFICATION forming part of Letters Patent No. 508,199, dated November 7, 1893.

Application filed May 31, 1893. Serial No. 476,172. (No model.)

To all whom it may concern:

Be it known that I, OTIS B. BENTON, a citizen of the United States, residing at Cleveland, in the county of Cuyahoga and State of Ohio, have invented certain new and useful Improvements in Electric Conduits for Tramways; and I do hereby declare that the following is a full, clear, and exact description of the invention, which will enable others skilled in the art to which it appertains to make and use the same.

My invention relates to that class of electric conduits for tramways which has a primary or main underground conductor that is put in electric touch with a secondary conductor divided into sections insulated from one another, the object being among other things to improve and simplify such conduits so that they may be not only cheaper of construction and easier to get at for repairs, but also that they may be applied to railways where the ties are placed in the ordinary manner, crosswise of the track, and the system thus be rendered available and practicable to varying conditions of road-beds.

In the accompanying drawings, Figure 1 is a longitudinal central sectional elevation of a conduit and its attachments and connections as it appears in one form of my invention in a road using common cross ties, the trolleys carried by the cars and the service conductor being shown above. Fig. 2 is a cross section of the construction shown in Fig. 1 on a line corresponding to α , α , Fig. 1. Fig. 3 is a side elevation of a section of the main pipe shown in cross section Figs. 1 and 2. Fig. 4 is a side elevation of a modified form of contact making mechanism, and Figs. 5 and 6 together illustrate still another modification, as hereinafter more fully described.

In my invention the main conductor B is placed in a tube A corresponding to an ordinary gas or water main six inches in diameter, or thereabout, which pipe or tube may be lined, if desired, with any insulating substance to assist in keeping out moisture. On the inside of and into the bottom of the pipe are screwed insulated standards or supports —2— one or two inches high. Along the tops of these rests the main conductor B. These supports may themselves be of insulating

material, or such material may be interposed between them and the conductor B so that the main conductor shall be wholly out of electric contact with the pipe A. The main pipe or tube A is laid lengthwise of the track, and if between the rails thereof, may be immediately below the ties. In the top of the pipe between the ties is a hole of suitable size, say three inches in diameter, more or less. Into this hole is screwed what may be a section or piece of gas pipe—3', although in some instances the parts A and —3— might be made in one piece. These short pipes project from the main pipe up above the ties and form small towers reaching to within several inches of the surface of the ground. At least one of these towers is inserted between each tie and there may be two, if preferred. The towers also may be lined with insulating material, if desired, to avoid possible loss of current. The top of each tower is covered closely with a diaphragm of rubber, leather, or other suitable water and dirt excluding material, or the cover may be of corrugated steel, in which case it must be fastened to a gutta-percha or like rim attached to the tower so as to be insulated therefrom. Directly above the line of the towers is the boxing or channel C, having a central longitudinal slot for the trolley or contact making arm —4— to run in.

In each of the tubes —3— is arranged a contact rod —5—, which extends through the diaphragm —6— to which it is affixed, and into position above to contact with service wire 7, and below to contact with main feed wire —B—, when contact is made. Otherwise, and normally, the rod —5— will be about an inch from the said main wire and with the circuit at that point wholly broken. The said rod —5— is stayed by insulating washers —9— and —10— in the tower or tube, so as to prevent coming into touch therewith, and its lower end is spread somewhat so as to make certain and effectual contact with the main conductor when pressed down upon it. The upper end of this contact rod stands immediately beneath the slot in the box or channel C, so as to be in line with the traveling contact maker on the car, and a suitable spring —11— between the washers —9— and —10— keeps the rod up out of touch with

main wire —B—. The washer —9— is fixed to the tower and the washer —10— to said rod, and the upper end of the rod —5— is fixed to the service wire —7—. When the 5 rod is pressed down from above the spring is thereby compressed on the lower washer, the upper washer moving up and down in the tower while the lower remains stationary.

Immediately under the slot and on the tops 10 of the rods —5— is the secondary or service wire —7—. This wire is divided into sections between the towers, and the sections are insulated from each other at —a— by any suitable means which serves also as a joint 15 or connection. The trolley wheels —12— are fixed to bent arm —4—, and as the trolley passes along this secondary conductor, pressing down the contact rods one after another into contact with the main conductor, the 20 current is collected to the car motor. Of course a device, as a shoe, shown in Figs. 4 and 5, or their equivalent, could be placed on the bottom of a car, which would pass along over the exposed tops of the contact 25 rods as the car moved and collect the current from the rods themselves direct to the car motor and thus dispense with the secondary or service wire. In order to get a sufficiently continuous current from a secondary conductor two or more trolley wheels are required, one following the other at the proper distance, and thus bridging the insulating joints and avoiding flashing and burning out at these points. 30

To entirely prevent sparking in making and breaking the contacts on the main wire, I provide two dead trolley wheels —13— and —14—, one of which goes before and the other after the conducting trolley. The dead 40 trolley wheels are of insulated material and serve to press the parts into contact so as to be together when the conducting trolley comes along. Thus, the one in advance serves to 45 depress the contact rod into mechanical touch with the main conductor before the trolley reaches that section of the service wire, and the dead trolley in the rear serves likewise to hold the rod down until the conducting trolley wheels have passed over onto the next 50

section of the service wire, after which contact can be broken without sparking. In case a secondary conductor as above described is not used in taking off the current from the contact rods, but instead a fixed rail or shoe 55 —15—, Fig. 4, I make the two ends 16, 16 of such rail or shoe of insulated material to answer the same purposes as a dead trolley wheel, the said rod being thereby held in mechanical contact with the main until after 60 the current has ceased to flow.

The main pipe I have described above could be placed centrally between a double tracked railway and with small towers extending to both sides under a rail and up between the 65 ties, be operated as in the manner described.

The conduit or tube is reached for inspection and repairs by removing the towers where needed. This would not interfere with the operation of the rest of the line, and makes 70 all parts and wires accessible at any time.

Having thus described my invention, what I claim as new, and desire to secure by Letters Patent, is—

1. The conduit for the feed wire, the service 75 boxing or channel, and the towers connecting said conduit and boxing, in combination with insulated flexible caps closely covering the tops of said towers, and contact makers in the towers passing through said caps and affixed 80 thereto, substantially as described.

2. In an electric system as described, a movable contact maker, a current conveyer connected with the car, and insulated means before and behind said conveyer to depress said 85 contact maker into contact, substantially as described.

3. In a system as described, the feed wire and the contact rods, a current conveying device connected with the car, and devices before and behind said current conveying device to depress said rods before and after 90 electrical contact is made therewith, substantially as described.

Witness my hand to the foregoing specification this 19th day of May, 1893.

OTIS B. BENTON.
